UNITED STATES PATENT OFFICE.

ARTHUR A. JOHNSON, OF NEW YORK, N. Y., ASSIGNOR TO UNDERWOOD TYPEWRITER COMPANY, OF NEW YORK, N. Y., A CORPORATION OF DELAWARE.

TYPEWRITING MACHINE.

Application filed November 16, 1922. Serial No. 601,213.

To all whom it may concern:

Be it known that I, ARTHUR A. JOHNSON, a citizen of the United States, residing in borough of the Bronx, in the county of the Bronx, city and State of New York, have invented certain new and useful Improvements in Typewriting Machines, of which the following is a specification.

This invention relates to typewriting machines, and more particularly to typewriting machines of the continuous billing type such as that disclosed in the patent to Wernery & Smith, No. 1,132,055. In a machine of this type, there is provided a rear carriage-extension which travels from side to side of the machine, with the carriage, on a rearward extension of the frame. Upon this carriage-extension is mounted a carbon-carriage movable toward and from the platen, to hold carbon-sheets interleaved with the folds of a continuous manifold web fed to the machine from the rear. The carbon-carriage is provided with stepped supports having holes therein for receiving studs on carbon-sheet-holding blades which extend alternately across the path of the webs from opposite sides thereof. Each blade is provided with a clip for clipping a carbon-sheet thereto.

It sometimes happens that the carbon-sheet is clipped to the carbon-blade in an incorrect angular position, that is, in a position in which the carbon-sheet will not be parallel to the direction in which the webs are fed to the machine. When long carbon-sheets are used, a slight error in the angular position in which a carbon-sheet is clipped to the carbon-blade will cause the portion of the sheet remote from the blade to be misplaced laterally to quite a substantial extent. It is difficult to determine exactly the proper position of attachment of the carbon-sheet to the blade, and, where the usual type of blade is used, this can only be done by repeated trials.

With the purpose in view of obviating this difficulty, a feature of the present invention consists in the provision of a carbon-carrying blade which is angularly adjustable on the carbon-carriage, whereby a carbon-sheet, clipped to the blade, may be brought into parallelism with the continuous work-webs by angular adjustment of the blade.

Another feature of the invention consists in the provision of a carbon-blade and means

for angularly adjusting the carbon-blade, so arranged that the angular position of the blade cannot be changed by a pull exerted upon the carbon-sheet.

Another feature consists in the provision of means for effecting a combined bodily and angular adjustment of the carbon-sheets.

Other features and advantages will hereinafter appear.

In the accompanying drawings,

Figure 1 is a plan view of parts of a typewriter of the continuous billing type having the present improvements applied thereto.

Figure 2 is a fragmentary plan view of the carbon-holder-adjusting means, on a larger scale than Figure 1.

Figure 3 is a longitudinal vertical section of the structure shown in Figure 2.

Figure 4 is a plan view, similar to Figure 2, showing the parts in a different adjusted position.

The typewriting machine, in common with other machines of this type, comprises a carriage (not shown) having a rearward extension 11 movable with the carriage in letter-feed direction by the usual carriage-propelling spring, not shown, and in the reverse direction by manual operation. This carriage-extension is supported and guided by the usual rearward extension of the machine-frame. A carbon-carriage 13 is provided for holding carbon-sheets 14 interleaved between the plies of work-webs 15, which may be either fan-fold webs or separate plies, and which are fed to the machine from the rear. This carbon-carriage is stepped to hold the carbon-sheets at suitable elevations, and, during writing operations, is drawn by the webs 15 toward the platen 16 at each line-spacing operation of the latter, being guided in such movement on rails 17, forming a part of the carriage-extension. The carbon-carriage 13 may be returned to the rear limit of its movement when a form has been completed, as explained in the patent to Wernery & Smith, above referred to, to bring the carbon-sheets 14 into co-operation with a fresh portion of the work-webs.

On each step 18 of the carbon-carriage 13 there is provided a short plate 19 having a slot 20 therein, which plate is fixedly, but detachably, secured to the carbon-carriage 13 by studs 21 which are received in holes 22 in the carbon-carriage. A circular cam 23 is eccentrically pivoted on the plate 19 to

extend above the upper surface thereof and is slidingly received in a closely-fitting circular opening 24 in the end of a carbon-carrying blade 25. A headed pivot-stud 26 connects a carbon-clip 27 to the carbon-blade 25, and has its head received in the slot 20 in the plate 19. A spacing washer 28, of substantially the same thickness as the carbon-clip, is positioned around the circular 10 cam 23 between the plate 19 and the carbon-blade 25. A threaded stem 29 extends upwardly from the center of the eccentrically-mounted circular cam 23, and is surrounded by a washer 30 which bears against the upper face of the carbon-blade 25. A knurled nut 31 for turning the eccentric is screwed upon this stem 29 to hold the plate 19, carbon-blade 25 and washers 28 and 30 in assembled position, and a second nut 32 is 20 screwed upon the stem to lock the first nut.

When a carbon-sheet 14, clipped by a blade 25 and clip 27 in the machine, is found to occupy a crooked position, the operator will turn the nut 31 on the stem 29 and 25 thereby rotate the eccentric cam 23 about its pivot. Rotation of the cam 23 will change the angular position of the carbon-blade 25 through the action of the cam on the walls of the circular opening 24 in the 30 blade, and of the slot 20 on the head of the stud 26, thus adjusting the angle of the carbon-sheet carried by the blade.

The ratio of the radius of the eccentric cam to the radius of the circular path traversed 35 by its center, and the co-efficient of friction between the carbon-blade and the peripheral surface of the eccentric are so related that it is not possible to turn the eccentric by force exerted upon the carbon-blade. There 40 is, therefore, no possibility of the angular adjustment of the blade being affected by the pull of the work-webs upon the carbon-sheet.

The angular adjustment of the carbon-holders is attended by some bodily movement, 45 and, while this is not great, it is possible that the carbon-sheet may, under some circumstances, be found to be misplaced bodily when the angular adjustment has been effected. Due to the nature of the adjusting 50 means, however, there will be two positions which a carbon-holder may occupy for every angular position assumed by it. Should the carbon-sheet be found to be misplaced bodily after its angular adjustment has been effected, the operator may adjust it bodily by 55 rotating the eccentric cam to move the blade to the other position in which it will bear the same angular relationship to the carbon-carriage.

60 The studs 21 on the plates 19 are arranged to co-operate with the holes ordinarily provided in the carbon-carriages of machines of this type for the direct attachment of relatively stationary carbon-blades. The 65 device disclosed herein is, therefore, capable

of being inserted in existing machines without alteration thereof.

Variations may be resorted to within the scope of the invention, and portions of the improvements may be used without others. 70

Having thus described my invention, I claim:

1. In a typewriting machine having a platen, a carbon-paper carriage movable toward and from the platen, a carbon-sheet-holder mounted on the carbon-paper carriage, and means for adjusting the carbon-sheet-holder angularly for bringing the carbon-sheet attached thereto completely into the field of the work and thereby compensating for skewed attachment of the carbon-sheet, and for retaining it in adjusted position. 75

2. In a typewriting machine, a carbon-sheet-holder for holding carbon-sheets interleaved with work-sheets, comprising carbon-sheet-clipping means, and means for angularly adjusting a carbon-sheet in the machine while it is clipped by said clipping means, and compensating for skewed attachment of the carbon-sheet to the clipping means. 80

3. In a typewriting machine, a carbon-paper-holder, and means for angularly adjusting the carbon-paper-holder and retaining it in adjusted position, comprising an eccentric, manually-operated means for adjusting the eccentric, and means co-operating with the eccentric to control the angular adjustment of the carbon-paper-holder. 85

4. In a typewriting machine, a carbon-paper-holder, a carbon-sheet-clip thereon a finger-piece rotatable by the operator, and connections between the finger-piece and the carbon-sheet-clip for causing the latter to be 10 angularly adjusted by rotation of the former, said connections being arranged to be inherently immovable by the carbon-sheet-clip, and so causing the clip to be positively retained in any position to which it is adjusted. 11

5. In a typewriting machine having a platen, a carbon-paper carriage movable toward and from the platen, carbon-sheet-clips mounted on the carbon-paper carriage, and means for individually adjusting carbon-sheets while held by said clips to cause their lateral edges to lie substantially in parallelism to the direction of movement of the carbon-paper carriage, the arrangement 11 being such that skewed attachment of the carbon-sheets to the clips can be compensated for, thus obviating repeated trials in the attachment of the carbon-sheets. 12

6. In a typewriting machine, a carbon-carriage, a slotted plate detachably secured thereto, a circular cam eccentrically mounted on the plate, a carbon-sheet-holder having an opening which encircles the cam, and a stud slidable in the slot of the plate, and 13

means for rotating the cam to change the angular position of the carbon-sheet-holder and thereby alter the position of a carbon-sheet held by it.

5 7. In a typewriting machine, a carbon-carriage, a slotted plate detachably secured thereto, a circular cam eccentrically mounted for rotation on said plate, a carbon-sheet-holder comprising a blade having an opening for cooperation with the circular cam, a pivot-stud on the blade, and a clip pivoted on the stud, the said stud extending into the slot in the blade, and means for turning the circular cam to adjust the angular position of the carbon-sheet-holder.

8. In a typewriting machine, a carbon-paper carriage, a support detachably secured to the carriage in fixed relationship thereto, a carbon-holder mounted on the support and angularly adjustable with relation thereto, and co-operating cams on the support and on the carbon-holder for effecting angular adjustments of the carbon-holder.

25 9. In a typewriting machine, a support, a carbon-sheet-holder mounted on the support for angular or bodily adjustment, either in a direction to correct the skewing of the carbon-sheet thereon, or in parallelism, and means for effecting such adjustments.

10. In a typewriting machine, a support, a carbon-sheet-holder mounted on the support, and means for adjusting the position and correcting the skewing of a carbon-sheet, including means for adjusting the carbon-sheet-holder to move the opposite

ends of a carbon-sheet held thereby either in the same or opposite directions laterally of the machine at the will of the operator. 40

11. For use in a continuous billing typewriting machine having a carbon-carriage, a carbon-holding device, comprising a base-member, means for attaching the base-member to the carbon-carriage, a carbon-holder 45 mounted for swinging movement on said base-member, means for swinging the carbon-holder relatively to the base-member, and means for positively preventing accidental swinging movement of the carbon-holder in either direction.

12. In combination, a carbon-holder, a fulcrum-member thereon, a support for said carbon-holder having a slot therein for receiving said fulcrum-member, and adjustable means on the support for moving the carbon-holder about the fulcrum in the slot to change the angular position of the carbon-holder.

13. In a typewriting machine, a carbon-sheet-holder, a support therefor, a pin-and-slot connection between the holder and support, and an eccentric pivoted on the support and encircled by the carbon-holder for co-operation therewith, said eccentric being 60 pivoted sufficiently near its center to preclude the possibility of its being turned by pressure of the carbon-holder upon its periphery.

ARTHUR A. JOHNSON.
